(57) **CLAIM**

The ornamental design for a vehicle mirror, as shown.

DESCRIPTION

FIG. 1 is a top and front perspective view a left vehicle mirror, showing our new design;

FIG. 2 is a bottom and front perspective view thereof;

FIG. 3 is a top and rear perspective view thereof;

FIG. 4 is a front elevational view thereof;

FIG. 5 is a rear elevational view thereof;

FIG. 6 is a left side elevational view thereof;

FIG. 7 is a right side elevational view thereof;

FIG. 8 is a top plan view thereof; and,

FIG. 9 is a bottom plan view thereof.

The broken lines represent portions of the vehicle mirror that forms no part of the claimed design.
